CIGARETTE HOLDER

Lewis M. Morton, Dallas, Tex.

Application July 19, 1946, Serial No. 685,005

3 Claims. (Cl. 131—194)

1

The present invention relates to cigarette holders and is more particularly concerned with an air-conditioned smoker's article.

The primary object of the invention is to provide a device of the character referred to which utilizes a current of fresh air to cause the tobacco to retain its crispness and to reduce heat and moisture in the tobacco to a minimum, thus rendering the smoke mild and cool.

Another object of the invention is to provide a simple and compact device of the character referred to which is designed to be manipulated by a thumb and a finger while smoking.

A further object of the invention is to provide a device of the character referred to which can be manufactured and sold at low cost.

With the foregoing and other objects and advantages in view the invention consists of the novel construction and arrangement of parts hereinafter described and claimed.

In the accompanying drawings illustrating the invention,

Figure 1 is a top plan view of the device.

Figure 2 is a side elevation view thereof.

Figure 3 is an elevation view of the opposite side.

Figure 4 is a partial horizontal sectional view taken on line 4—4 of Figure 2.

Figure 5 is a partial vertical longitudinal sectional view taken on line 5—5 of Figure 4.

Figure 6 is an enlarged fragmentary sectional view taken on line 6—6 of Figure 5.

Figure 7 is an enlarged transverse sectional view taken on line 1—1 of Figure 1, and

Figure 8 is an enlarged transverse sectional view taken on line 8—8 of Figure 1.

Like numerals, as used in the description and drawings, designate the same parts of construction.

10 is the tubular or hollow body of the cigarette holder formed with a chamber therein which is preferably made of plastic. It has a round reduced end 11 suitably recessed to form a cavity, as at 12, for insertion of a cigarette and the opposite reduced round end 11' is designed for use as a bit or mouthpiece having a smoke emitting passage 13 therethrough. Preferably the bit is shaped, as at 14, to better fit between the lips.

A smoke conduit 15 extends longitudinally through the body from the cavity 12 in the end for the cigarette to the mouth piece or bit being to one side and devoid of communication with the chamber. Where it communicates with said cavity, the conduit is deflected by an elbow enlargement 16.

2

The body 10 is provided on top and bottom with transverse openings 17 and 18 which communicate with the chamber and which extends between the shoulders 17' and 18' of the body but short thereof.

Located inside the body chamber and exposed through the openings 17 and 18 is a cylindrical, flexible member 19, preferably of rubber and designed to serve as a bellows. Attached to 10 the top and bottom of said member, preferably with glue, are two thin plates 20 positioned inside the openings 17 and 18, and constructed of plastic, aluminum or other suitable material. These serve, when pressed in by thumb and finger, 15 to compress the member 19 and expel air therefrom through a round passage 21 communicating with the conduit at said elbow enlargement 16 and the flexible members or bellows 19.

Fitted in said passage 21 is a metallic sleeve 22 20 formed with a flared inner end 23 which forms a seal between the sleeve and the rubber member or bellows 19, through the end of which the sleeve projects. Located in said sleeve is a reciprocable, annular valve 24, the valve 24 having a closed end 32, Figure 6, said valve 24 being normally retracted by a coiled spring 25 attached at one end to a pin 26 which extends across the flared end of sleeve 22 and at the other end to a pin 27 which extends across the inside of valve 24 adjacent its inner orifice. The annular valve 24, when forced outwardly against the tension of the spring, closes the conduit 15 at the elbow and is provided on its upper side with a port 28 designed to serve as an outlet for air which is forced through sleeve 21 by compression of rubber cylinder 19. When the two plates 20 are pressed inward with the fingers, the air passing through said sleeve, will urge the annular valve outward against the tension of spring.

40 In the opposite end of the bellows is an air intake port 29 which is controlled by a flap valve 30 preferably of thin rubber, located inside the air chamber in position to close same when the rubber cylinder is compressed. This intake port 45 communicates with a breather hole 31 in the top of the body contiguous to the mouth piece 13.

In operation the reciprocable valve 24 moves forward and exposes the outlet port 28 only when there is manipulation of the flexible bellows.

At such time the valve 30 closes the intake 29 but when the flexible bellows have been collapsed and plates 20 released, air comes through said port from the breather hole 31, thus expanding 55 the bellows. These operations serve the purposes

of the device best, when had between draws on the cigarette.

It will be understood that this air-conditioning device may be readily adapted to a cigar holder and such embodiment would be within the spirit and scope of the claims.

As different embodiments may be made of this inventive concept and modifications may be made in the embodiment hereinbefore shown and described, it will be understood that the matter herein is to be interpreted as illustrative merely, and not in a limiting sense.

What I claim is:

1. A cigarette holder comprising an elongated body formed with an elongated chamber therein, said body being formed with an opening leading into at least one side of said chamber, said body being formed at one end with a cavity to receive an end of a cigarette, a bit at the opposite end of said body formed with a bore therethrough, an elongated bellows confined in said chamber and exposed through said opening for manual compression, said bellows having a valved air inlet, an air passage formed in said body and providing communication between said bellows and said cavity, a longitudinal smoke passage formed in said body at one side of and out of communication with said chamber, one end of said smoke passage opening into the bore of said bit and the other end of said smoke passage opening into said cavity, and valve means comprising an element reciprocally mounted in said air passage normally occupying an air passage closing position wherein said bellows is out of communication with said cavity, said element being displaceable by air discharged by said bellows upon compression of said bellows to another position in which said element closes said other end of said smoke passage while opening said air passage whereby air discharged by said bellows passes into said cavity.

2. A cigarette holder comprising an elongated body formed with an elongated chamber therein, said body being formed with an opening leading into at least one side of said chamber, said body being formed at one end with a cavity to receive an end of a cigarette, a bit at the opposite end of said body formed with a bore therethrough, an elongated bellows confined in said chamber and exposed through said opening for manual compression, said bellows having a valved air inlet, an air passage formed in said body and providing communication between said bellows and said cavity, a longitudinal smoke passage formed in

said body at one side of and out of communication with said chamber, one end of said smoke passage opening into the bore of said bit and the other end of said smoke passage opening into said cavity, and valve means comprising an element reciprocally mounted in said air passage normally occupying an air passage closing position wherein said bellows is out of communication with said cavity, said element being displaceable by air discharged by said bellows upon compression of said bellows to another position in which said element closes said other end of said smoke passage while opening said air passage whereby air discharged by said bellows passes into said cavity, and means secured to the side of said bellows and projecting through said body opening from said chamber which may be engaged to manually compress said bellows.

3. A cigarette holder comprising a hollow body formed with a cavity in one end thereof for receiving an end of a cigarette, a bit at the opposite end of said body having a smoke passage therethrough, said body having a longitudinal conduit therein which connects said smoke passage with said cavity, said conduit being devoid of communication with the interior of said hollow body, said body being provided with an opening extending longitudinally therethrough intermediate the ends thereof, a bellows within the interior of said body and exposed through said opening for manual compression, an air passage leading from said bellows to said cavity, and a reciprocal valve means in said air passage normally closing the same and arranged to open upon compression of said bellows whereby the air from said bellows is discharged into said cavity, said valve means having an element uncovering said conduit in the normal or closed position of said valve means and closing said conduit in the open position of said valve means.
